UNITED STATES PATENT OFFICE.

WILLIAM H. SEMON, OF CLEVELAND, OHIO.

HOLDER FOR REMOVABLE OBJECTS.

1,061,412.

Specification of Letters Patent.

Patented May 13, 1913.

Application filed May 4, 1911. Serial No. 625,106.

To all whom it may concern:
Be it known that I, WILLIAM H. SEMON, a citizen of the United States, resident of Cleveland, county of Cuyahoga, and State 5 of Ohio, have invented a new and useful Improvement in Holders for Removable Objects, of which the following is a specification, the principle of the invention being herein explained and the best mode in 10 which I have contemplated applying that principle, so as to distinguish it from other inventions.

This invention relates to a holder for removable objects, and more particularly to 15 such as embody a clamping finger normally in engagement with a primary supporting member.

The object is to provide a device of this 20 general character which, while economical of manufacture, will be more easy of manipulation and yet more efficient.

The said invention consists of means 25 which are hereinafter fully described and particularly set forth in the claim.

20 The annexed drawings and the following description set forth in detail certain means embodying my invention, the disclosed means, however, constituting but one of various mechanical forms in which the principle of the invention may be applied.

In said annexed drawings:—Figure 1 is 30 an elevation of a holder embodying my invention. Fig. 2 is an enlarged view partly in section. Fig. 3 is a vertical section on line III—III of Fig. 2. Fig. 4 is a view similar to Fig. 3, of a modified part thereof.

Referring more particularly to the drawings, in which like letters of reference refer 35 to similar parts throughout the several views, a hollow tube A is provided internally at each end thereof with an abutting partition a', having the centrally disposed lug a². At each extremity of the tube A, a hollow cap B is fixedly mounted in any 40 approved manner. These caps are of such a shape that the upper portions extend toward each other, somewhat above the tube, where they are provided with the openings b', clearly appearing in Fig. 2. One end of 45 the clamping fingers C extends through these openings b', and conforms substantially to the interior contour of the caps. Near the extremity of the ends c' and specifically so as to be disposed upon the axis of the tube A, are lugs c² which may be exact counterparts of the

lugs a², and are adapted to coöperate therewith in a manner to be presently manifest. The clamping fingers C are pivotally mounted in the openings b' through the medium of the pins c³. The other ends of the clamping fingers are of hollow construction and made to flare, as best seen in Fig. 3, and designated by the reference letters c⁴. Pivotally mounted upon the pins d' extending through the openings c⁵ in these flaring portions of the clamping fingers, are rollers D. The constructive arrangement is moreover such that these pins will lie in a parallel plane with the pins c³.

70 Springs E are interposed between the partitions a' and the ends c', so as to surround, and be supported upon the lugs a² and c², as clearly appearing in Fig. 2. As will now be apparent, these springs, as calculated, are adapted to normally hold the 75 rollers D in yielding engagement with the upper surface of the tube A, whereby a towel, robe, or other object F to be supported thereon may be readily slipped underneath the rollers, and more or less securely held in position. It should be especially noted that while the construction permits the very ready lateral insertion of the object F such as the towel shown which it is desired to have the holder support, quite 80 an appreciable resistance is offered, tending to prevent its slipping downward from the tube A. It is this which is deemed to comprise the inventive feature of this application, and in so far as the applicant is aware, 85 differentiates it from previous constructions placed upon the market.

In Fig. 4, a modification of somewhat less merit is shown. In this form, a ball G is mounted in a ball-bearing construction c⁶ 95 formed on the under side of the upper end c⁴ of the clamping finger. While this form permits an insertion of the object to be clamped with equal facility either from the sides or from the ends, the resistance offered 100 against lateral slipping is necessarily lessened.

Having fully described my invention, what I claim therefore and desire to secure by Letters Patent is:—

105 A holder for removable objects comprising the combination of a supporting tube having an open extremity; the hollow cap B secured to the latter and itself provided with the opening b'; the clamping member 110

C pivoted to said cap and having its extremity extending within the latter; the holder provided with the lug c^2 ; the spring E mounted within said tube having its outer end engaging the extremity c' of the member C, and its inner end abutting the fixed partition a' ; and the anti-friction

roller D normally in engagement with the surface of said rod.

Signed by me, this 2nd day of May, 1911.

W. H. SEMON.
